UNITED STATES PATENT OFFICE.

WALKER LEE, OF BIGPRAIRIE, OHIO.

MUSIC-LEAF TURNER.

1,270,745.

Specification of Letters Patent. Patented June 25, 1918.

Application filed November 17, 1917. Serial No. 202,550.

To all whom it may concern:

Be it known that I, WALKER LEE, a citizen of the United States, residing at Bigprairie, in the county of Holmes and State 5 of Ohio, have invented new and useful Improvements in Music-Leaf Turners, of which the following is a specification.

This invention relates to music leaf turners and it consists in the novel features hereinafter described and claimed.

An object of the invention is to provide a turner of simple and durable structure which may be applied to the music shelf of a piano or similar instrument or to a music stand 15 which may be easily and quickly manipulated for the purpose of turning a sheet of music at such time as it is desired to effect the same.

With this object in view the turner comprises a clamp adapted to be applied to the shelf or stand with a tube adjustably mounted thereon and a spring supported rod traversing the length of the tube. A sleeve is mounted at the upper end of the tube and a second tube is connected with one end of the sleeve. A spring pressed rod is located in the last mentioned tube and the sleeve and is provided with a notch adapted to receive the upper end of the first mentioned rod 25 whereby the second mentioned rod may be held at a retracted position against the tension of the spring adapted to actuate the same. A head is carried at the end of the second mentioned tube and a lever is pivoted therein and connected with the second mentioned rod. A fork member is pivoted upon the free end of the lever and receives between the branches of its fork a pin which is attached to the head. An arm is attached 30 to the said fork and extends beyond the head and a spring clip is mounted upon the arm and carries a depending rod. The clip is adapted to receive a sheet of music between its opposite side portions and the rod 35 extends behind the sheet and the parts are so arranged that when the rod which is slidably mounted in the first mentioned tube is depressed it releases the second mentioned rod which is actuated by the spring which 40 operates upon the same whereby the lever is swung which in turn swings the fork and the arm attached thereto whereby the clip and rod attached to the clip turn the sheet of music.

In the accompanying drawings:— 55

Figure 1 is a front elevation of the music leaf turner.

Fig. 2 is a top plan view of the same.

Fig. 3 is a rear view of the leaf engaging means. 60

Fig. 4 is a sectional view of the leaf turning mechanism.

Fig. 5 is a sectional view of the retaining means for the leaf turning mechanism.

Fig. 6 is a sectional view of the support 65 for the leaf turner.

The music leaf turner comprises a clamp member 1 which is provided with a screw 2 whereby the frame may be secured to a shelf or stand in a usual manner. A tube 3 passes vertically through the clamp member 1 and is adjustably secured therein by means of a set screw 4 which is threaded in the clamp member and adapted to bear at its inner end against the side of the tube. It is apparent that by loosening the set screw the tube 3 may be adjusted vertically in the clamp member and when at a desired position may be secured by tightening the said set screw. The said screw is provided at its lower end with a longitudinally disposed recess 5. A rod 6 traverses the length of the tube 3 and the said rod is provided at its lower end with an angularly disposed extremity 7 which is normally received in the 70 recess 5 of the said tube. A spring 8 is connected at one end with the rod 6 and the other end of the said spring bears against a collar 9 which is located at a fixed point within the tube 3. The spring 8 is under 75 tension with a tendency to normally hold the extremity 7 of the rod 6 in an elevated position in the recess 5 of the tube 3. However, the said rod may be depressed by exerting pressure in a downward direction 80 upon the extremity and then the rod may be turned whereby the extremity is carried under the lower end of the tube and the upper end of the rod 6 may thus be held below the upper end of the said tube. 85

The music leaf turner also includes a sleeve 10 which is provided in the vicinity of one end with an aperture 11 adapted to snugly receive the upper end of the tube 3. A set screw 12 is provided at one end of the 90 sleeve 10 and is adapted to engage against the side of the tube 2 whereby the sleeve 10 is held upon the tube. It is apparent that 105

by loosening the set screw 12 the sleeve 10 and the parts attached thereto and herein-after explained, may be detached from the tube 3 and thus the parts may be compactly 5 assembled for carrying in a music case or other receptacle. A tube 13 is connected at one end with the sleeve 10 in the vicinity of the aperture 11 and a head 14 is carried at the other end of the tube 13. A rod 15 traverses the length of the sleeve 10 and tube 13 and the end portions of the said rod project beyond the ends of the sleeve and tube. The rod 15 is provided at one end with a knob 16 and the other end of the 10 said rod enters the head 14 herein before referred to. A coil spring 17 is located in the sleeve 10 and bears at one end against a fixed portion of the sleeve and at its other end bears against the collar 18 which is 15 mounted on the rod 15. The spring 17 is under tension with a tendency to hold the rod 15 in a retracted position in the tube and sleeve. The rod 16 is provided at its lower side with a notch 19 which is adapted 20 to receive the upper end of the rod 6 when the said rod 6 is elevated by the action of the spring 8 hereinbefore described.

A lever 20 is pivotally mounted in the head 14 and one end of the rod 15 is pivotally connected with the said lever at a 30 point between the ends of the lever. A fork member 21 is pivotally mounted at the free end of the lever 20 and the branches of the fork of the said member receive a pin 22 which is mounted at the upper side of the head 14. The head 14 is provided with an opening 23 and an arm 24 is attached to the fork member 21 and extends through the opening 23 beyond the side of the head 14. 35 A spring clip 25 is slidably mounted upon the arm 24 and is of conventional form or pattern such as the ordinary spring clip or clamp used for gripping articles of apparel or sheets of paper for securing them together. A rod 26 depends from the clip 25 and is provided at its lower end with an angularly disposed extremity 27 which may extend below the lower edge of a sheet of music. The upper portion of the sheet of 40 music may be secured in the clip 25.

It is apparent that when the rod 15 is moved in an inward direction by applying pressure to the knob 16 the notch 19 in the said rod 15 will be brought over the upper 45 end of the rod 6 and inasmuch as the said rod 6 is forced in an upward direction by the spring 8 the upper end of the rod 6 will

enter the notch 19 whereby the rod 15 is held in a retracted position. When the said rod 15 is retracted it swings the lever 20 whereby the fork member 21 is swung and the arm 24 is held approximately in alinement with the tube 13. The sheet of music is then secured in the clip 25 and extending over the extremity 27 of the rod 26. When it is desired to turn the sheet of music the rod 6 is depressed by exerting pressure in a downward direction upon the extremity 7 thus removing the upper end of the rod 6 from the notch 19 and under the influence of the 50 spring 17 the rod 15 is projected to move longitudinally in the sleeve 10.

This movement on the part of the rod 15 swings the lever 20 whereby the fork member 21 which is in contact with the pin 22 swings upon the lever 20 carrying the arm 24 with it and inasmuch as the rod 26 is behind the sheet of music the said sheet is turned and the side thereof which previously was reversed is brought to view and 55 becomes the obverse side of the sheet.

From the foregoing description taken in conjunction with the accompanying drawings, it will be seen that a music leaf turner of simple and durable structure is provided 60 and that the same may be easily and quickly manipulated to effect the turning of a sheet of music.

Having described the invention what is claimed is:—

1. A music leaf turner comprising a clamp, a tube attached to the clamp, a spring pressed rod located in the tube, a leaf turning means mounted on the tube and including a spring for actuating the same, a set screw for detachably securing the leaf turning means to the tube, the leaf turning means being engageable by the rod to hold the same at a state of rest.

2. A music leaf turner comprising a tube, 100 a spring pressed rod located in the tube and provided with a notch, means engageable in the notch for holding the said rod at a retracted position, a head carried by the tube, a lever fulcrumed in the head and pivotally connected with the rod, a fork member pivoted on the lever, a pin carried by the head and received between the branches of the fork member, an arm carried by the fork member and extending through the head 105 and leaf engaging means carried by the arm.

In testimony whereof I affix my signature.

WALKER LEE.
